[57] CLAIM

The ornamental design for a cover for colostomy or ileostomy pouch, as shown and described.

DESCRIPTION

FIG. 1 is a perspective view of a first embodiment of a cover for a colostomy or ileostomy pouch according to the present invention;

FIG. 2 is a front elevational view of the cover of FIG. 1;

FIG. 3 is a rear elevational view of the cover of FIG. 1;

FIG. 4 is a leftside view of the cover of FIG. 1; and

FIG. 5 is a plan view of the cover of FIG. 1.

The conventional sealing ring is shown in broken lines for illustrative purposes only.

FIG. 1

FIG. 2

FIG. 3
